UNITED STATES PATENT OFFICE.

FREDERICK DRISSELER, OF NEW YORK, N. Y.

SAFETY-CLASP FOR PINS, BUTTONS, AND THE LIKE.

1,368,124.

Specification of Letters Patent.

Patented Feb. 8, 1921.

Application filed November 17, 1920. Serial No. 424,654.

To all whom it may concern:

Be it known that I, FREDERICK DRISSELER, a citizen of the United States, and a resident of the city of New York, borough of the Bronx, in the county of Bronx and State of New York, have invented a new and Improved Safety-Clasp for Pins, Buttons, and the like, of which the following is a full, clear, and exact description.

10 This invention relates to safety holding devices for buttons, pins, badges and other similar devices and has for an object to provide an improved construction which will be very effective when in position but 15 which is easily applied and removed.

Another object of the invention is to provide a safety holding construction associated with a pin or button which will hold the pin or button in place without changing 20 the position or disturbing the usual appearance of the pin.

A still further object of the invention more specifically is to provide a sliding clasp coacting with a particular form of pin 25 shank for producing an interlocking action.

In the accompanying drawing—

Figure 1 is a front view of part of a garment with a badge applied thereto and the fastening means embodying the invention 30 shown in dotted lines.

Fig. 2 is a rear view of the structure shown in Fig. 1.

Fig. 3 is a vertical section through Fig. 1 on line 3—3.

Fig. 4 is a transverse sectional view through Fig. 1 on line 4—4.

Fig. 5 is a front view of the fastener shown in Fig. 2.

Fig. 6 is a rear perspective view of the 40 badge shown in Fig. 1.

Referring to the accompanying drawing by numerals, 1 indicates a garment to which the badge 2 is connected. It will be understood that the badge 2 provided with the pin 45 3 may be connected to any garment at substantially any point and be retained in place by the retaining member 4. As shown in Fig. 6, pin 3 is provided with a body 5 having a spur 6 and a piercing shank 7. The 50 section 8 connecting body 5 with the shank 7 is provided with a pair of notches 9 for receiving the edges 10 and 11 of the plate 12. Plate 12 is provided with a slot 13 wide enough to accommodate the neck 14 so that 55 the plate 12 may freely slide into the position shown in Fig. 2 and when in such po-

sition the neck 14 will snap into the enlargement 15 of slot 13. This action is permitted by reason of the slit 16 extending almost to the lower end of the plate 12 whereby the 60 plate is more or less resilient. The plate 12 is also provided with a pair of fingers 17 at each end adapted to be folded over and against the guide plate 18, said guide plate being formed with a pressed up bead 19 65 whereby a groove is provided which easily accommodates the shank 7. The plate 18 is provided with guiding ears 20 and 21 which limit the spreading movement of the arch of the plate 12 though permitting a 70 sufficient resiliency to secure the results herefore mentioned.

In operation, when it is desired to place the badge 2 in position on the garment 1, the pin 3 is arranged as shown in Fig. 3 or as 75 near that position as possible and then the pointed end of shank 7 inserted into the bead 19 after which the retaining member 4 is slid upwardly until it assumes the position shown in Fig. 3. As it moves upwardly 80 it will compress the cloth or garment 1 and thereby cause the spur 6 to pierce the cloth and in this way give two points of support for the badge 2.

The clasp has been shown in connection 85 with an ornamental badge but it will be evident that it may be used for other forms of badges or buttons of any kind or other devices which may use a pin similar to pin 3.

What I claim is:—

1. A safety clasp for buttons or the like comprising a pin member connected with the button having a rearward extending spur and a shank spaced from the button extending parallel to the button and a sliding 95 clamping member slidingly fitted onto said parallel section, said clamping member having means for interlocking with said parallel shank.

2. A safety clasp for buttons and the like 100 comprising a pin member secured to the button formed with a rearward extending section having a notch therein and a shank parallel to the button, a clasping member formed with a groove so that it may slide 105 over said parallel shank, said clasping member having a pair of gripping members, one of said members sliding in said notch.

3. A safety clasp for buttons and the like 110 comprising a pin member having a rearward extending section provided with a pair of oppositely positioned notches and a shank

parallel to the button and a gripping member coacting with said pin structure, the gripping member comprising a back plate or body having a groove therein and a front 5 gripping plate formed with a slot merging into a notch, said gripping plate being adapted to extend into said notches as said back plate is slidably moved over said shank, said sliding movement continuing 10 until the notch in the gripping plate snaps over the rearward extending section of the pin structure.

4. A safety clasp for buttons and the like comprising a pin structure connected with 15 the button formed with a section extending rearwardly and a parallel shank, and a gripping member co-acting with said pin structure, said gripping member comprising a body having a groove and a gripping plate 20 having a substantially centrally arranged slot merging into a notch whereby when the

body is positioned so that the shank may slide in said groove the gripping plate will slide over the rearward extending section of 25 said pin section until said rearward extending section snaps into the notch in said gripping plate.

5. A safety clasp for buttons and the like comprising a pin structure adapted to be connected with the button and a clamping 30 member co-acting with said pin structure, said clamping member comprising a gripping plate having a slot extending through part of its length and merging into a notch, said plate being formed with a plurality of gripping 35 fingers and a back plate formed with a groove for receiving part of said pin structure, said back plate being held in place by said fingers and said back plate being also provided with a pair of pins for limiting 40 the resiliency of said gripping plate.

FREDERICK DRISSLER.
